A. P. RISSLER

BRAKE BEAM AND METHOD OF CONSTRUCTING SAME

Filed March 16, 1925

UNITED STATES PATENT OFFICE.

ALBIN P. RISSSLER, OF CHICAGO, ILLINOIS, ASSIGNOR TO CHICAGO RAILWAY EQUIPMENT COMPANY, OF CHICAGO, ILLINOIS, A CORPORATION OF ILLINOIS.

BRAKE BEAM AND METHOD OF CONSTRUCTING SAME.

Application filed March 16, 1925. Serial No. 15,936.

This invention relates to new and useful improvements in brake beams and method of constructing the same and has for its object the provision of a brake beam in which the fulcrum or strut member is secured in position and held against movement on the beam without the use of extraneous attaching devices and without the necessity of perforating or cutting away portions of either one of said members.

5

Further objects of the invention are to provide a method of brake beam construction wherein the strut or fulcrum member after being placed on the beam member is subjected to pressure or pinched at points 15 adjacent to said beam member, thereby offsetting portions of the latter and forming shoulders which abut and engage the sides of the fulcrum member and prevent the 20 latter from moving longitudinally on said beam member.

With these and other objects in view, my invention consists in certain novel features of construction and arrangement of parts, 25 hereinafter more fully described and claimed, and illustrated in the accompanying drawings, in which—

Figure 1 is a top plan view of a brake beam showing the strut member in position 30 thereon.

Figure 2 is an enlarged vertical cross section taken on line 2—2 of Figure 1.

Figure 3 is a top plan view of the same.

Figure 4 is an enlarged cross section taken 35 on line 4—4 of Figure 2.

Figure 5 is a detail view showing in dotted lines the position of the portions of the respective members before pressure is applied thereto.

40 Figure 6 shows a modified form of strut member.

Figure 7 illustrates another method of indenting the strut and the beam for the purpose of holding said strut against movement.

Years of experience have shown that the punching of a hole in the compression member of a brake beam and riveting a strut to same or slotting the compression member for the same purpose materially weakens the compression member and very frequently leads to breakage at this point after the brake beam has been placed in service. This tendency to breakage is aggravated by 55 the camber which it is necessary to place in

the beam. To eliminate these objectionable features, I have provided a brake beam in which the strut or fulcrum member is held in position and locked against lateral movement by vertically disposed shoulders which are formed in the flanges of the compression member and abut the sides of the strut member. These shoulders are formed by indenting the flanges of the compression member after the strut is placed in position thereon 60 and the pressure necessary to offset or indent the flanges is applied to the strut at the appropriate points, which pressure is thereby transmitted to the portions of the flanges of the compression member, thus insuring proper seating of the strut in the offset portion and providing a perfect fit therebetween.

The drawings illustrate a trussed type of 65 brake beam as indicated at 10, on the ends of which are mounted brake heads 11. This brake beam comprises a compression or 70 brake beam member 12, tension member 14, and a fulcrum or strut member 15, which latter is suitably apertured for receiving the 75 pivot pin of the lever of the brake mechanism. This strut member is made from a forging which is bent to form a recess or seat 80 16 for embracing the compression member 12 and the arms 15^a of member 15 are spaced 85 from each other and secured together by a rivet 17 interposed between said arms to maintain the latter in proper relation.

The extremities of arms 15^a are attached 90 by a rivet or rivets 19 to a filler block 20 in which is formed a seat 21 for receiving tension member 14. In order to prevent lateral movement of the strut longitudinally of the compression member, portions of the toes of the flanges of the latter are depressed 95 or offset as indicated at 22 to provide vertically disposed shoulders 22^a which abut the sides of the strut and hold the latter against lateral movement. The strut member 15 is completed with the exception of rivets 17 100 and is placed in proper location on the compression member 12. Pressure is then applied to the strut as indicated at α thereby pinching the strut at points where it laps the channel toes, thus depressing both strut 105 and channel toes as indicated in Figure 5 and forming shoulders 22^a which lock the strut member against movement. The rivet 17 is then driven in position, thereby firmly 110 clamping the strut in the indenture or seat

made in the toes of the channel of brake beam 12. In this manner, the compression member or the strut member is not weakened and they are firmly interlocked with each other.

In the form shown in Figure 6 a strut member 24, instead of wholly embracing the beam member, has the ends of arms 24^a formed with opposed seats 25 for engaging and only partially embracing the beam member.

The form shown in Figure 7 has the transverse or bridge portion 15^b which bears against the web portion 12^b of the beam member 12 indented or struck as indicated at 26, thereby forming an inwardly projecting protuberance 27 which enters into interlocking engagement with a recess or depression 28 formed in the web portion 12^b formed therein either in the same operation or formed independently before the assembly of the members.

Thus an efficient and inexpensive method is provided for holding the fulcrum member against movement relative to the beam member while the strength of the latter is not impaired.

Obviously, various other modifications could be made without departing from the spirit of my invention.

I claim:

1. In a brake beam construction, the combination of a flanged beam member having transverse depressions in the toe portions of the flanges thereof, and a U-shaped strut member embracing said beam member and having depressed portions seated in said depressions of said beam member, thereby preventing lateral movement of said strut member relatively to said brake beam member.

2. In a brake beam construction, the combination of a flanged beam member having transverse depressions in the edges of its flanges, a U-shaped strut member embracing said beam member and having deflected portions seated in the depressions of said beam member, and means engaging said strut member adjacent to said brake beam member for clamping said strut member in position in said depressions, thereby interlocking said members against displacement relative to each other.

3. A brake beam construction comprising a flanged beam member having formed in the edges of its flanges indentures or depressions aligned with each other, and a strut member embracing said beam and having its parallel portions deflected to center said depressions and hold said strut against lateral movement.

4. A brake beam construction comprising a flanged beam member and a U-shaped fulcrum member embracing said beam member and pinched at points adjacent to the edges of the flanges thereof whereby said strut

member occupies transverse depressions thus formed in said edge portions and is held thereby against lateral movement.

5. A brake beam construction comprising a flanged beam member and a fulcrum member engaging said beam member and pinched at points adjacent to the edges of the flange portions thereof whereby said strut member occupies depressions formed transversely in said flange portions and is held thereby against lateral movement, and means in the sides of said strut member adjacent to said beam member for clamping said strut in said depressions made in the flange portions of said beam member.

6. In a brake beam construction, the combination of a channel-shaped compression member, a strut member embracing said compression member, a filler block secured to the ends of said strut member and provided with a seat adapted to receive the tension member, and fastening means engaging the sides of said strut member adjacent to said compression member for clamping said strut member in position thereon, the edges of the flanges of said compression member being offset inwardly for a distance equal to the width of said strut member to provide seats having vertically disposed shoulders in abutting engagement with the sides of said strut member to prevent lateral movement of the latter.

7. The method of constructing brake beams consisting in placing a strut member in encompassing relation on a flanged beam member and pinching said strut member at points coincident with the edges of the flange portions of said beam member, thereby depressing said flange portions and said portions of the strut member simultaneously whereby the latter is interlocked with said brake beam against lateral movement.

8. The method of constructing brake beams consisting in placing a U-shaped strut member on a flanged beam member and pinching the parallel portions of said strut member at points coincident with the edges of the flange portions of said beam member, thereby depressing said edge portions and said parallel portions of the strut member whereby the latter is held against lateral movement, and clamping said strut member firmly against the depressed portions of said beam member.

9. The method of constructing brake beams consisting in forming a strut member with a transverse seat for receiving a compression member, placing said strut in position on said compression member, subjecting said strut to pressure at points coincident with the edges of the flange portions of said compression member, thereby indenting said flange portions transversely and forming vertically disposed shoulders in abutting engagement with the sides of said strut mem-

ber for holding the latter against movement longitudinally of said compression member.

10. The method of constructing brake beams consisting in forming a strut member with a transverse seat for receiving a compression member, placing said strut in position on said compression member, subjecting said strut to pressure at points coincident with the edges of the flange portions of said compression member, thereby indenting said flange portions and forming therein transversely and vertically disposed shoulders in

abutting engagement with the sides of said strut member for holding the latter against movement longitudinally of said compression member, and securing the spaced sides of said strut member at points adjacent to said compression member together for firmly clamping said strut in position on the compression member. 15

20 In testimony whereof I hereunto affix my signature this 12th day of March, 1925.

ALBIN P. RISSLER.
